UNITED STATES PATENT OFFICE.

BRADFIELD HAMILTON, OF FOSTORIA, OHIO.

FURNACE.

SPECIFICATION forming part of Letters Patent No. 768,851, dated August 30, 1904.

Application filed December 30, 1903. Serial No. 187,218. (No model.)

To all whom it may concern:

Be it known that I, BRADFIELD HAMILTON, a citizen of the United States, residing at Fostoria, in the county of Seneca and State 5 of Ohio, have invented a new and useful Furnace, of which the following is a specification.

This invention relates to improvements in furnaces, and has for its principal object to provide an improved construction of air-heating furnace which, while comparatively simple and inexpensive, will possess a maximum heating capacity and will thoroughly utilize the combustible content of the fuel, so that the products of combustion which escape to 15 the chimney will carry with them a minimum amount of waste heat.

A further object of the invention is to provide in a furnace of this character improved means for supplying air to the combustion-chamber in order to render more effective the combustion of the gaseous constituents of the fuel.

A further object of the invention is to provide a furnace of this type with an improved arrangement of draft devices by means of which the draft of the furnace may be maintained through a circuitous route in order to impart a large amount of heat to the radiating-surfaces or made direct from the combustion-chamber to the chimney at will.

In attaining the objects above enumerated I make use of the novel construction and combination of parts of a furnace hereinafter fully described, illustrated in preferred form 35 in the accompanying drawings, and having the novel features thereof specifically pointed out in the appended claims, it being understood that changes in the form, proportions, and exact mode of assemblage of the elements 40 exhibited may be resorted to without departing from the spirit of the invention or sacrificing the advantages thereof.

In the drawings, Figure 1 is a view in side elevation of the improved furnace. Fig. 2 is 45 a longitudinal sectional view of the same. Fig. 3 is a front elevation. Fig. 4 is a horizontal sectional view. Fig. 5 is a sectional detail view taken on the plane indicated by the line 5-5 in Fig. 2.

50 Referring to the drawings, in which corre-

sponding parts are designated by similar characters of reference throughout the several views, 1 designates an approximately rectangular casing comprising an upper fire-box 2 and combustion-chamber 3, communicating with the fire-box at the bottom, and a lower ash-pit 4, the ash-pit being separated from the combustion-chamber and fire-box by a horizontally-disposed grate 5, which consists, preferably, of a single casting undercut 55 at the rear and longitudinally-movable upon supporting-ledges 6. Above the fire-box and combustion-chamber is a dome 7, separated from the fire-box and combustion-chamber by a plate 8, having a plurality of openings 60 therein, as shown. The outer surface of the casing 1 at the sides of the fire-box and combustion-chamber is provided with radiating ribs or ridges 9, and similar ribs or ridges are provided upon the exterior of the dome 7, 65 which is securely bolted through the casing 1, as shown in Fig. 1. The fire-box 2 and combustion-chamber 3 are partially separated by a curved back plate 10, supported upon projecting brackets 11, formed upon the inner 70 surface of the side walls of the casing 1, and a narrow passage 12 is left between the lower margin of the back plate 10 and the upper surface of the grate 5. The grate 5 is arranged for longitudinal sliding movement, as 75 above stated, and is consequently a little shorter than the casing 1, the rear end of the grate being normally in contact with the end wall of the casing 1, as shown in Fig. 2, and the forward end of the grate being spaced a 80 short distance from the front wall of the casing. To prevent the passage of fuel through the opening between the end of the grate and the front wall of the casing 1, an inclined shield 13 is provided above the opening, and 85 the shield is provided with perforations to permit the passage of air from the ash-pit into the fire-box when desired.

The grate is arranged for sliding movement instead of the usual oscillatory movement of 95 independent grate-bars in order to insure the discharge of ashes from the grate with a minimum loss of combustible fuel, and the mechanism employed in imparting sliding movement to the grate consists, preferably, of a 100

clevis 14, pivoted at the front of the grate, a shaking-bar 15, adapted for engagement with said clevis, and a socket 16, adapted to receive the lower end of the shaking-bar to afford a fulcrum therefor. Except when the mechanism above mentioned is in use to effect the discharge of ashes from the grate, the clevis is turned inward against the end of the grate, so that the door 17, leading into the 10 ash-pit, may be closed; but when it is desired to shake the grate the door 17 is opened and the clevis is swung outward into the position shown in Fig. 2, so that the shaking-bar may be passed downward through the eye at the 15 free end of the clevis and introduced into the socket 16.

The products of combustion are usually allowed to pass from the gaseous combustion-chamber 3, at the rear end of the casing 1, into 20 the space between the circular drum 18 and the surrounding drum 19. The drum 18 and its support are ordinarily cast in one piece, as shown in Fig. 1, and the drum 19 is secured in a groove or channel provided therefor at the rim of the support of the drum 18. At the top of the drum 18 and drum 19 is a 25 plate 20, having a central opening, which is disposed over the interior of the drum 18 and openings or passages 20^a at the rear of the 30 plate, separated by a cross-bar 20^b, which permit the products of combustion to pass upward from the drum 18 and the drum 19 into an annular space between an inner drum 21 and an outer drum 22, concentric therewith, 35 both of which drums are supported upon the upper surface of the plate 20. The annular space between the drums 21 and 22 is closed at the top by an annulus 23, secured in position, as shown in Fig. 2, and the products of 40 combustion pass from said annular space through a smoke-pipe 24 to a drum 25, mounted above the dome 7 and connected with said dome by means of a thimble 26, provided on the top of the drum and having a damper 27 pivoted therein, as shown in Fig. 2. The damper 45 27 is operated by means of a rod 28, extending to the front of the furnace and provided with a hand-wheel 29. From the drum 25 the smoke passes through a pipe 30, which 50 extends upon a very slight upward incline to the chimney. (Not shown.)

In order to facilitate the combustion of the gases in the chamber 3, at the rear of the fire-box, air-conduits 31 are arranged at the sides 55 of the fire-box, as shown in Figs. 1 and 2, these conduits being provided at their outer ends with closures 32 and discharging at their inner ends into the chamber 3. When the furnace is in operation, the current established by the passage of the products of combustion into the space between the drum 18 and the drum 19 draws air through the conduits 31 at a rate determined by the strength 60 of the draft and the amount of opening permitted at the outer ends of said conduits.

When passing through the conduits 31, the air necessarily comes into contact with the highly-heated side walls of the fire-box, and when the air passes into the chamber 3 it is heated to such a high temperature that it greatly facilitates combustion in the chamber and causes the complete consumption of the smoke and carbon monoxid which pass into the combustion-chamber from the fire-box. 70

To permit the use of the furnace for heating water, if desired, water-pipes 33 are arranged in the heated dome 7, as best seen in Figs. 1 and 3, and the cleaning of the drums and flues of the furnace is permitted by removable caps 34, fitted in annular flanges 35, 80 projecting from the rear surface of the drum 22 and the forward surface of the drum 25. 75

A door 36 is provided at the front of the fire-box, as usual, and in the top of the door 17 of the ash-pit is provided a pivoted flap 37, by 85 means of which the draft from beneath the fire-box may be controlled.

From the foregoing description and the drawings illustrative thereof it will be clearly evident that the furnace is simple and comparatively inexpensive in construction, that it presents a maximum of radiating-surface, and that the supply of air to the fire-box and combustion-chamber is so arranged that all the heating effect of the fuel may be obtained. 90

In order to secure the full heating effect from the furnace, the draft from the fire-box and combustion-chamber will be maintained through the circuitous passage around the drums 18 and 21 and thence through the pipe 100 24 and the drum 25; but when it is desired to produce a quick and effective draft the damper 27, between the dome 7 and the drum 25, will be opened, and direct draft from the fire-box to the drum 25 and smoke-pipe 30 will be produced. 105

Having thus described the construction and operation of my invention, what I claim as new, and desire to secure by Letters Patent, is— 110

1. In a furnace, a fire-box, a grate therein, supporting-brackets formed interiorly upon the walls of said fire-box, a curved back plate supported upon said brackets and spaced from the grate which forms the bottom of the fire-box, air-flues disposed exterior of and constituted partly by the walls of the fire-box and opening into the gas-combustion chamber in rear of the curved back plate, radiating means for conveying the products from said gas-combustion chamber to a point of exit. 115

2. In a furnace, a fire-box, a grate therein, brackets formed interiorly upon the side walls of the fire-box, a curved back plate supported upon said bracket and spaced from the grate which constitutes the bottom of the fire-box, thus forming a constricted passage connecting the lower portion of said fire-box with the gas-combustion chamber separated from the fire-box by the curved back plate, radiating-drums 120 125 130

disposed behind said gas-combustion chamber and communicating therewith through an opening substantially midway between the bottom and the top of said combustion-chamber, and means for supplying hot air to the upper portion of said combustion-chamber.

3. In a furnace, a fire-box, a radiating-dome above said fire-box and having openings in the floor thereof to afford communication with said fire-box, a smoke-drum above said dome connected by suitable flues with said fire-box, and a damper disposed between said drum and said dome, whereby direct draft may be established from said fire-box through said dome to 15 said drum.

4. In a furnace, a fire-box, a rear drum arranged behind said fire-box and communicating with the same and extending upward therefrom, a front drum located above said 20 fire-box, a pipe connecting said drums, and a smoke-pipe extending rearward from the front drum.

5. In a furnace, a fire-box, a rear drum arranged behind said fire-box and communicating therewith, said drum extending upward above the top of said fire-box, a front drum located above said fire-box and connected with the rear drum, and a smoke-pipe extending 25

rearward from the upper part of said front drum over said rear drum.

6. In a furnace, a fire-box, a gas-combustion chamber behind said fire-box and communicating therewith, a rear drum behind said gas-combustion chamber and communicating therewith, said rear drum having a central 30 vertical opening and being composed of inner and outer shells spaced apart to afford a passage for the products of combustion, plates connecting the shells at the top and bottom, a horizontal diaphragm mounted in the space 35 between the inner and outer shells at a point above the opening through which products of combustion pass from the gas-combustion chamber, said diaphragm being provided with openings at the back of the drum, a front 40 drum above the fire-box connected with the upper portion of the rear drum, and a smoke-pipe leading rearward from said front drum.

In testimony that I claim the foregoing as my own I have hereto affixed my signature in 45 the presence of two witnesses.

BRADFIELD HAMILTON.
